UNITED STATES PATENT OFFICE.

WILLIAM J. FRISBIE, OF CHICAGO, ILLINOIS, ASSIGNOR TO JUSTRITE MANUFACTURING COMPANY, OF CHICAGO, ILLINOIS, A CORPORATION OF ILLINOIS.

SPARK-PRODUCING MECHANISM.

Application filed February 8, 1922. Serial No. 535,023.

To all whom it may concern:

Be it known that I, WILLIAM J. FRISBIE, a citizen of the United States, and a resident of Chicago, in the county of Cook and State 5 of Illinois, have invented certain new and useful Improvements in Spark-Producing Mechanism, of which the following is a specification.

My invention relates to spark producing 10 mechanism for producing sparks for igniting gas issuing from an orifice and is particularly adaptable and useful in connection with miners' acetylene lamps.

The invention relates to that class of spark 15 producing mechanism in which is provided a friction wheel and pyrophoric material for cooperating therewith, together with an adjusting lever and a spring which returns the lever when released, an important object of my invention being to provide improved ratchet mechanism compactly and 20 efficiently arranged with the lever, wheel and other parts to lock the wheel against rotation when the lever is positively swung but to connect the wheel with the lever to 25 rotate with the lever when it is released, to thereby cause the wheel to cooperate with the pyrophoric material to produce sparks for igniting the gas issuing from the burner 30 with which the mechanism is associated.

My improved construction and arrangement is clearly illustrated on the accompanying drawing in which—

Fig. 1 is a front elevational view of a 35 miner's cap lamp,

Fig. 2 is an enlarged side elevational view of the spark producing attachment with one of the frame walls partly broken away and the reflector in section,

Fig. 3 is an enlarged sectional view on plane 3—3 Fig. 2,

Fig. 4 is an outside elevational view of the actuating lever of the spark producing mechanism,

Fig. 5 is an inside view of the lever with the spring pawl therein, and

Fig. 6 is a side view of the friction wheel showing the ratchet tooth arrangement.

I have shown my invention applied to a 50 miner's cap lamp which as shown comprises a water container A, a carbide cup B, a gas tip C, a reflector D concentric with the gas tip, and lever mechanism E for controlling the water supply valve of the lamp. The 55 spark producing attachment comprises a

base 10 having an exteriorly threaded barrel 11 extending therefrom which has the longitudinal bore 12 for receiving a compression spring 13 and a block of pyrophoric material 14, a cap 15 receiving the end of the 60 barrel. Extending from the opposite sides of the base are the parallel opposed walls 16 and 17 having the openings 18 and 19 respectively for receiving the tubular pivot pin 20. Surrounding the pin between the walls 65 16 is bushing 21, and encircling this bushing is the coiled spring 22. The spring is surrounded by the bearing flange 23 extending from the hub 24 of the lever 25, and this flange is surrounded by the annular friction 70 wheel or disc 26, the pyrophoric material being held by the spring 13 against the friction wheel.

The hub 24 of the lever 25 has also the peripheral flange 27 which with the inner bearing flange 23 provides the annular pocket 28 for the spring pawl member 29. This pawl member is, as shown, in the form of a flat three-quarters circular spring whose one end 30 is deflected at right angles to extend through the hole 31 provided in the hub 24 of the lever, the pawl being then anchored at this end. The other end 32 of the pawl is turned outward slightly to form a pawl point or tooth. The friction wheel 80 on its side next to the lever hub has the annular row of ratchet teeth 33 with which the pawl point 32 cooperates. The friction wheel opening 34 receives the inner bearing flange 23 of the lever hub 24 and the hub is 90 of sufficiently smaller diameter than the wheel so as not to interfere with proper co-operation of the friction teeth 35 of the wheel with the pyrophoric material when the wheel is rotated.

The lever 25 has the side wall 36 provided with the longitudinal slot 37 which communicates with the lever opening 38, and the end 39 of the spring 22 extends along this slot and hooks around the edge 100 of the wall 25 as clearly shown in Fig. 2. The lever hub engages with the wall 16 on the base 10, and between the wall 17 and the friction wheel is inserted a washer 40, which has the flange 40' extending therefrom into the wheel opening 34 to form a continuation of the bearing flange 23 on the lever. The washer has the slot 41 therethrough through which extends the end 42 of the spring 22, this end hooking around 110

the wall 17 as clearly shown in Fig. 2. The slot 41 permits the spring end to operate freely between the wheel and the wall 16 when the lever is swung.

- 5 The sparking attachment is secured on the reflector D of the lamp with the friction wheel in a diametral plane including the burner tip, the reflector having a hole d through which the barrel 11 extends with
- 10 the base 10 against the inside of the reflector, the nut 43 threading on the barrel 11 and engaging against the outside of the reflector. The spring 22 is arranged to resist inward swing of the lever toward the burner tip and to normally hold the lever against the edge of the reflector as clearly shown in Fig. 2. The frictional engagement of the pyrophoric material with the wheel caused by the spring 13 will resist rotation of the
- 15 wheel, and the spring pawl 29 and the ratchet teeth on the wheel are so arranged that when the lever is swung inwardly the pawl point will glide over the ratchet teeth without rotating the wheel. When the lever
- 20 is released after inward swing thereof the spring will return it to outer position and during outward swing the pawl point will cooperate with the ratchet teeth to rotate the wheel to produce sparks, the spring 22
- 25 overcoming the friction of the pyrophoric material against the wheel. The produced sparks will then ignite the gas issuing from the burner tip and the lamp will be lighted.
- To insure ignition of the lamp in a
- 30 draught, or when the pressure in the carbide cup is low, I provide another wall 44 on the lever which with the wall 36 forms a channel 45 which, when the lever is swung in, will bridge between the gas tip and the
- 35 friction wheel to receive and conduct gas towards the wheel so that when the lever is released the sparks will ignite the conducted gas and the flame will be transmitted to the tip to light the lamp. The end of
- 40 the lever is preferably expanded to form a cap 46 which, when the lever is swung inwardly, will be directly in front of the tip outlet to receive the gas and guide it through the channel 45. When the cap is brought
- 45 close to the tip it will also more or less restrict and retard the outflow of gas, so that should the pressure in the lamp be low the outflow can be retarded for a moment until the pressure picks up and then when
- 50 the lever is released sufficient gas will be discharged to insure ignition of the lamp. The rounded back of the cap 46 will also permit the lever to be readily engaged by the finger and swung to inner position.
- 55 My improved arrangement is very practical and efficient. The various parts are all compactly and concentrically nested together between the walls 16 and 17 of the supporting frame and yet have sufficient
- 60 clearance to function properly. The ratchet

mechanism, particularly, is very compact and efficient and the wheel is rotated only in one direction so that the entire serrated periphery of the wheel is utilized for sparking purposes. I do not desire to be limited to the exact construction and arrangement shown and described as modifications can be made which will still come within the scope of the invention.

I claim as follows:

1. In spark producing mechanism of the class described, the combination of a frame, a pivot pin on said frame, a coiled spring surrounding said pin, a friction wheel surrounding said spring and concentric therewith, a lever concentric with said spring and adjacent to said wheel, said spring being connected at one end to said lever and its other end to said frame, ratchet teeth on one side of said wheel, a ratchet pawl on said lever for cooperating with said teeth, pyrophoric material and means for holding it against said wheel, said pawl passing along said wheel without rotating it when the lever is swung in one direction but causing rotation of said wheel when the lever is returned in the opposite direction by said spring, rotation of said wheel relative to said pyrophoric material causing the production of gas igniting sparks.

2. In sparking mechanism of the class described, the combination of a supporting frame having opposed walls, a pivot pin extending between said walls, a lever, an inner flange on said lever receiving said pin, a friction wheel receiving and rotatable on said flange, said wheel having ratchet teeth on its side adjacent to said lever, a flat arcuate pawl spring between said wheel and lever, said spring being secured at one end to said lever and having its other end deflected to form a pawl point for engaging with said ratchet teeth, a coiled spring surrounding said pin and located within said flange, one end of said spring being anchored to said lever and the other end being anchored to said frame, pyrophoric material, and means for frictionally engaging said material with said wheel, said spring tending to resist swing of said lever and to return it after swing thereof, said pawl spring traveling idly over said wheel ratchet teeth when the lever is swung but cooperating with the teeth when the lever is returned by its spring to rotate said wheel against the pyrophoric material to produce ignition sparks.

3. In spark producing mechanism of the class described the combination of a frame, a pivot pin on said frame, a lever hub and a lever extending therefrom, said hub having an inner bearing flange concentric with said pin and having an outer peripheral flange, said flange forming an annular pocket, an annular spark wheel receiving said inner

flange, an annular row of ratchet teeth on said wheel projecting into said pocket, a flat arcuate pawl spring in said pocket anchored at one end to the hub and having its 5 other end forming a pawl point for cooperating with said ratchet teeth, a coiled spring surrounding said pin and located within said inner hub flange, one end of said spring being anchored to said lever and the 10 other end being anchored to said frame, pyrophoric material, and means for frictionally engaging said material with said wheel, said coiled spring tending to resist swing of said lever and to return it after a swing, said 15 pawl spring engaging idly over the ratchet teeth when the lever is positively swung but cooperating with said teeth to rotate said wheel when the lever is returned by its spring, rotation of said wheel causing cooperation thereof with said pyrophoric material to produce sparks.

4. In spark producing mechanism of the class described, the combination of a support having opposed walls, a pivot pin extending between said walls, a lever formed of sheet metal and having a hub receiving said pin, an arcuate pawl spring on the inner face of 90 said hub anchored at one end thereto and at its other end presenting a pawl point, a friction wheel surrounding said pin and having ratchet teeth on its one face for cooperating with said pawl point, a coiled spring 95 surrounding said pin and located within the hub and wheel and having one end anchored to said lever and its other end anchored to said frame, pyrophoric material, and means for frictionally engaging said material with said wheel, said spring tending to resist swing of said lever and to return it 100 after swing thereof, said pawl point traveling idly over said wheel when the lever is swung and cooperating with said ratchet 105 teeth to rotate the wheel when the lever is returned by its spring, rotation of the wheel causing the producing of gas igniting sparks.

5. In spark producing mechanism of the 110 class described, a combination of a supporting frame having opposed walls, a pivot pin extending between said walls, a lever having a hub flange receiving said pin, a friction wheel journaled on said hub and flange, pawl and ratchet mechanism between said wheel and hub, a spring anchored to said lever and to said frame for resisting swing of said lever and for returning it 115 after swing thereof, pyrophoric material, and means for frictionally engaging said material with said wheel, said pawl and ratchet mechanism operating idly when the lever is swung but cooperating to cause rotation of said wheel when the lever is re- 120 turned by its spring, rotation of said wheel causing cooperation thereof with said pyrophoric material to produce sparks.

6. In spark producing mechanism of the 125 class described, the combination of a sup- 130

opposite side of said wheel to form a continuation of said inner flange on the hub, a coiled spring surrounding said pin and located within said inner flange and bushing, one end of said spring being anchored to said 70 lever and the other end being anchored to said frame, said bushing having a slot through which said other end of the spring extends, said spring tending to resist swing of said lever and to return it after swing 75 thereof, pyrophoric material, and means for frictionally engaging said material with said wheel, said pawl tooth traveling idly over said ratchet teeth when the lever is positively swung but cooperating with said teeth 80 to rotate said wheel when it is returned by its spring, rotation of said wheel causing cooperation thereof with said pyrophoric material to produce sparks.

6. In spark producing mechanism of the 85 class described, the combination of a frame having opposed walls, a pivot pin extending between said walls, a lever formed of sheet metal and having a hub receiving said pin, an arcuate pawl spring on the inner face of 90 said hub anchored at one end thereto and at its other end presenting a pawl point, a friction wheel surrounding said pin and having ratchet teeth on its one face for cooperating with said pawl point, a coiled spring 95 surrounding said pin and located within the hub and wheel and having one end anchored to said lever and its other end anchored to said frame, pyrophoric material, and means for frictionally engaging said material with said wheel, said spring tending to resist swing of said lever and to return it 100 after swing thereof, said pawl point traveling idly over said wheel when the lever is swung and cooperating with said ratchet 105 teeth to rotate the wheel when the lever is returned by its spring, rotation of the wheel causing the producing of gas igniting sparks.

7. In spark producing mechanism of the 110 class described, a combination of a supporting frame having opposed walls, a pivot pin extending between said walls, a lever having a hub flange receiving said pin, a friction wheel journaled on said hub and flange, pawl and ratchet mechanism between said wheel and hub, a spring anchored to said lever and to said frame for resisting swing of said lever and for returning it 115 after swing thereof, pyrophoric material, and means for frictionally engaging said material with said wheel, said pawl and ratchet mechanism operating idly when the lever is swung but cooperating to cause rotation of said wheel when the lever is re- 120 turned by its spring, rotation of said wheel causing cooperation thereof with said pyrophoric material to produce sparks.

8. In spark producing mechanism of the 125 class described, the combination of a sup- 130

porting frame having opposed walls, a pivot pin extending between said walls, a bushing extending between said walls and surrounding said pin, a lever having a bearing flange surrounding said bushing, a friction wheel journaled on said bearing flange, pawl and ratchet mechanism between said wheel and lever, pyrophoric material, means for frictionally engaging said material with said wheel, and a spring anchored to said lever and to said frame for resisting swing of said lever and for returning it after swing thereof, said pawl and ratchet mechanism being idle when the lever is swung but operating to rotate said wheel when said lever is returned by its spring, rotation of said wheel relative to said pyrophoric material causing the production of gas igniting sparks.

9. In spark producing mechanism of the class described, the combination of a supporting frame having opposed walls, a pivot pin extending between said walls, a bushing surrounding said pin between said walls, a lever having a hub surrounding said bushing, a friction wheel journaled on said hub to rotate thereon, pawl and ratchet mechanism between said wheel and lever, a spring inserted on said bushing and located within said hub, said spring being anchored at one end of said lever and at its other end to said frame to resist swing of said lever and to return it after a swing thereof, pyrophoric material, and means for frictionally engaging said material with said wheel, said pawl and ratchet mechanism being idle when said lever is swung but operating to rotate said wheel when said lever is returned by its spring, rotation of said wheel relative to said pyrophoric material causing the production of sparks.

10. In spark producing mechanism of the class described, the combination of a supporting frame having opposed walls, a pivot pin extending between said walls, a bushing on said pivot pin between said walls, a lever formed of sheet metal and having a bearing flange surrounding said bushing, a coiled spring within said bearing flange and surrounding said bushing, said spring being anchored at one end to said lever and its other end to said frame to resist swing of said lever and to return it after a swinging movement, an annular friction wheel journaled on said bearing flange, an arcuate pawl spring on said lever having its one end anchored to said lever and its other end forming a pawl point, teeth on the adjacent face of said friction wheel with which said pawl point may cooperate, pyrophoric material, and means for frictionally engag-

ing said material with said wheel, said pawl point traveling idly over said ratchet teeth when the lever is swung but cooperating with said teeth to rotate said wheel when the lever is returned by its spring, the rotation of said wheel against said material causing sparks.

11. In spark producing mechanism of the class described, the combination of a supporting frame having opposed walls, a pivot pin extending between said walls, an annular sheet metal disc having an inner bearing flange for receiving said pin, an arcuate pawl spring on said flange anchored at one end to said disc and having its other end deflected to form a pawl point, a friction wheel journaled on said flange and having ratchet teeth on its adjacent face with which the pawl spring may cooperate, an actuating lever extending from said disc, a coiled spring surrounding said pin and located within said bearing flange, one end of said spring being anchored to said lever and the other end being anchored to said frame to resist swing of said lever and to return it after a swinging operation, pyrophoric material, and means for frictionally engaging said material with said wheel, said pawl and ratchet teeth being idle when said lever is swung but cooperating to cause rotation of said wheel when said lever is returned by its spring, cooperation of said wheel with said pyrophoric material causing the production of sparks.

12. In spark producing mechanism of the class described, the combination of a supporting frame having opposed walls, a pivot pin extending between said walls, a lever receiving said pin, a ratchet wheel receiving said pin, pawl and ratchet mechanism between said wheel and lever, a coiled spring around said pin and located within said lever and wheel, one end of said spring being anchored to said lever and the other end being anchored to said frame whereby said spring will resist swing of said lever and return it after a swinging operation, pyrophoric material, and means for frictionally engaging said material with said wheel, said pawl and ratchet mechanism permitting said lever to be swung independently of said wheel but cooperating to cause rotation of said wheel when said lever is returned by its spring, rotation of said wheel relative to said pyrophoric material causing sparks.

In witness whereof, I hereunto subscribe my name this 3rd day of February A. D., 1922.

WILLIAM J. FRISBIE,
